The ornamental design for a folding stand, as shown and described.

DESCRIPTION

FIG. 1 is a front left perspective view of a closed configuration of a folding stand showing our new design;
FIG. 2 is a rear left perspective view thereof;
FIG. 3 is a rear orthographic view thereof;
FIG. 4 is a front orthographic view thereof;
FIG. 5 is a left side orthographic view thereof;
FIG. 6 is a right side orthographic view thereof;
FIG. 7 is a top orthographic view thereof; and,
FIG. 8 is a bottom orthographic view thereof.

The dashed lines shown in FIGS. 1-8 are included for the purpose of illustrating environmental subject matter only and form no part of the claimed design.

The two concentrically-arranged circles shown in solid lines in FIGS. 1, 2, and 5 are claimed subject matter. The area located between the outer and inner circles, and the area located within the inner circle, is unclaimed subject matter. The unshaded area located between the broken lines appearing on the front face of the right leg of the folding stand (as oriented in FIG. 1) is unclaimed subject matter.
